CLAIM

The ornamental design for a dry packaging for heart valve, as shown and described.

DESCRIPTION

FIG. 1 is a perspective view of an embodiment of a dry packaging for heart valve in a closed configuration;
 FIG. 2 is a front view of the embodiment of FIG. 1 in a closed configuration;
 FIG. 3 is a rear view of the embodiment of FIG. 1 in a closed configuration;
 FIG. 4 is a left side view of the embodiment of FIG. 1 in a closed configuration;
 FIG. 5 is a right side view of the embodiment of FIG. 1 in a closed configuration;
 FIG. 6 is a top view of the embodiment of FIG. 1 in a closed configuration;
 FIG. 7 is a bottom view of the embodiment of FIG. 1 in a closed configuration;
 FIG. 8 is a perspective view of the embodiment of FIG. 1 in an open configuration;
 FIG. 9 is a left side view of the embodiment of FIG. 1 in an open configuration;
 FIG. 10 is a right side view of the embodiment of FIG. 1 in an open configuration;
 FIG. 11 is a top view of the embodiment of FIG. 1 in an open configuration;
 FIG. 12 is a bottom view of the embodiment of FIG. 1 in an open configuration.
 FIG. 13 is a perspective view of another embodiment of a dry packaging for heart valve in a closed configuration;
 FIG. 14 is a perspective view of the embodiment of FIG. 13 in an open configuration;
 FIG. 15 is a front view of the embodiment of FIG. 13 in a closed configuration;
 FIG. 16 is a top view of the embodiment of FIG. 13 in an open configuration;

FIG. 17 is a top view of the embodiment of FIG. 13 in a closed configuration;

FIG. 18 is a bottom view of the embodiment of FIG. 13 in an open configuration;

FIG. 19 is a bottom view of the embodiment of FIG. 13 in a closed configuration.

FIG. 20 is a perspective view of another embodiment of a dry packaging for heart valve in a closed configuration;

FIG. 21 is a perspective view of the embodiment of FIG. 20 in an open configuration;

FIG. 22 is a front view of the embodiment of FIG. 20 in a closed configuration;

FIG. 23 is a left side view of the embodiment of FIG. 20 in a closed configuration;

FIG. 24 is a right side view of the embodiment of FIG. 20 in a closed configuration;

FIG. 25 is a top view of the embodiment of FIG. 20 in an open configuration;

FIG. 26 is a top view of the embodiment of FIG. 20 in a closed configuration;

FIG. 27 is a bottom view of the embodiment of FIG. 20 in an open configuration;

FIG. 28 is a bottom view of the embodiment of FIG. 20 in a closed configuration.

FIG. 29 is a perspective view of another embodiment of a dry packaging for heart valve in a closed configuration;

FIG. 30 is a front view of the embodiment of FIG. 29 in a closed configuration;

FIG. 31 is a rear view of the embodiment of FIG. 29 in a closed configuration;

FIG. 32 is a left side view of the embodiment of FIG. 29 in a closed configuration;

FIG. 33 is a right side view of the embodiment of FIG. 29 in a closed configuration;

FIG. 34 is a top view of the embodiment of FIG. 29 in a closed configuration;

FIG. 35 is a bottom view of the embodiment of FIG. 29 in a closed configuration;

FIG. 36 is a perspective view of the embodiment of FIG. 29 in an open configuration;

FIG. 37 is a left side view of the embodiment of FIG. 29 in an open configuration;

FIG. 38 is a right side view of the embodiment of FIG. 29 in an open configuration;

FIG. 39 is a top view of the embodiment of FIG. 29 in an open configuration;

FIG. 40 is a bottom view of the embodiment of FIG. 29 in an open configuration.

FIG. 41 is a perspective view of another embodiment of a dry packaging for heart valve in a closed configuration;

FIG. 42 is a perspective view of the embodiment of FIG. 41 in an open configuration;

FIG. 43 is a front view of the embodiment of FIG. 41 in a closed configuration;

FIG. 44 is a top view of the embodiment of FIG. 41 in an open configuration;

FIG. 45 is a top view of the embodiment of FIG. 41 in a closed configuration;

FIG. 46 is a bottom view of the embodiment of FIG. 41 in an open configuration;

FIG. 47 is a bottom view of the embodiment of FIG. 41 in a closed configuration.

FIG. 48 is a perspective view of another embodiment of a dry packaging for heart valve in a closed configuration;

FIG. 49 is a perspective view of the embodiment of FIG. 48 in an open configuration;
FIG. 50 is a front view of embodiment of FIG. 48 in a closed configuration;
FIG. 51 is a left side view of embodiment of FIG. 48 in a closed configuration;
FIG. 52 is a right side view of embodiment of FIG. 48 in a closed configuration;
FIG. 53 is a top view of embodiment of FIG. 48 in an open configuration;
FIG. 54 is a top view of the embodiment of FIG. 48 in a closed configuration;
FIG. 55 is a bottom view of the embodiment of FIG. 48 in an open configuration;
FIG. 56 is a bottom view of the embodiment of FIG. 48 in a closed configuration.
FIG. 57 is a perspective view of another embodiment of a dry packaging for heart valve in a closed configuration;
FIG. 58 is a front view of the embodiment of FIG. 57 in a closed configuration;
FIG. 59 is a rear view of the embodiment of FIG. 57 in a closed configuration;
FIG. 60 is a left side view of the embodiment of FIG. 57 in a closed configuration;
FIG. 61 is a right side view of the embodiment of FIG. 57 in a closed configuration;
FIG. 62 is a top view of the embodiment of FIG. 57 in a closed configuration;
FIG. 63 is a bottom view of the embodiment of FIG. 57 in a closed configuration;
FIG. 64 is a perspective view of the embodiment of FIG. 57 in an open configuration;
FIG. 65 is a left side view of the embodiment of FIG. 57 in an open configuration;
FIG. 66 is a right side view of the embodiment of FIG. 57 in an open configuration;
FIG. 67 is a top view of the embodiment of FIG. 57 in an open configuration;
FIG. 68 is a bottom view of the embodiment of FIG. 57 in an open configuration.
FIG. 69 is a perspective view of another embodiment of a dry packaging for heart valve in a closed configuration;
FIG. 70 is a perspective view of the embodiment of FIG. 69 in an open configuration;
FIG. 71 is a front view of the embodiment of FIG. 69 in a closed configuration;
FIG. 72 is a top view of the embodiment of FIG. 69 in an open configuration;
FIG. 73 is a top view of the embodiment of FIG. 69 in a closed configuration;
FIG. 74 is a bottom view of the embodiment of FIG. 69 in an open configuration;
FIG. 75 is a bottom view of the embodiment of FIG. 69 in a closed configuration.
FIG. 76 is a perspective view of another embodiment of a dry packaging for heart valve in a closed configuration;
FIG. 77 is a perspective view of the embodiment of FIG. 76 in an open configuration;
FIG. 78 is a front view of the embodiment of FIG. 76 in a closed configuration;
FIG. 79 is a left side view of the embodiment of FIG. 76 in a closed configuration;
FIG. 80 is a right side view of the embodiment of FIG. 76 in a closed configuration;

FIG. 81 is a top view of the embodiment of FIG. 76 in an open configuration;
FIG. 82 is a top view of the embodiment of FIG. 76 in a closed configuration.
FIG. 83 is a bottom view of the embodiment of FIG. 76 in an open configuration;
FIG. 84 is a bottom view of the embodiment of FIG. 76 in a closed configuration.
FIG. 85 is a perspective view of another embodiment of a dry packaging for heart valve in a closed configuration;
FIG. 86 is a front view of the embodiment of FIG. 85 in a closed configuration;
FIG. 87 is a rear view of the embodiment of FIG. 85 in a closed configuration;
FIG. 88 is a left side view of the embodiment of FIG. 85 in a closed configuration;
FIG. 89 is a right side view of the embodiment of FIG. 85 in a closed configuration;
FIG. 90 is a top view of the embodiment of FIG. 85 in a closed configuration;
FIG. 91 is a bottom view of the embodiment of FIG. 85 in a closed configuration;
FIG. 92 is a perspective view of the embodiment of FIG. 85 in an open configuration;
FIG. 93 is a left side view of the embodiment of FIG. 85 in an open configuration;
FIG. 94 is a right side view of the embodiment of FIG. 85 in an open configuration;
FIG. 95 is a top view of the embodiment of FIG. 85 in an open configuration;
FIG. 96 is a bottom view of the embodiment of FIG. 85 in an open configuration.
FIG. 97 is a perspective view of another embodiment of a dry packaging for heart valve in a closed configuration;
FIG. 98 is a perspective view of the embodiment of FIG. 97 in an open configuration;
FIG. 99 is a front view of the embodiment of FIG. 97 in a closed configuration;
FIG. 100 is a top view of the embodiment of FIG. 97 in an open configuration;
FIG. 101 is a top view of the embodiment of FIG. 97 in a closed configuration;
FIG. 102 is a bottom view of the embodiment of FIG. 97 in an open configuration;
FIG. 103 is a bottom view of the embodiment of FIG. 97 in a closed configuration.
FIG. 104 is a perspective view of another embodiment of a dry packaging for heart valve in a closed configuration;
FIG. 105 is a perspective view of the embodiment of FIG. 104 in an open configuration;
FIG. 106 is a front view of the embodiment of FIG. 104 in a closed configuration;
FIG. 107 is a left side view of the embodiment of FIG. 104 in a closed configuration;
FIG. 108 is a right side view of the embodiment of FIG. 104 in a closed configuration;
FIG. 109 is a top view of the embodiment of FIG. 104 in an open configuration;
FIG. 110 is a top view of the embodiment of FIG. 104 in a closed configuration.
FIG. 111 is a bottom view of the embodiment of FIG. 104 in an open configuration; and,
FIG. 112 is a bottom view of the embodiment of FIG. 104 in a closed configuration.

The broken lines in the drawings depict portions of the dry packaging for heart valve that form no part of the claimed design.
